UNITED STATES PATENT OFFICE.

ALBERT F. CHACE, OF BOSTON, MASSACHUSETTS, ASSIGNOR OF ONE-HALF
TO JOHN S. MOULTON, OF SAME PLACE.

VELOCIPED.

SPECIFICATION forming part of Letters Patent No. 433,720, dated August 5, 1890.

Application filed January 24, 1890. Serial No. 338,003. (No model.)

To all whom it may concern:

Be it known that I, ALBERT F. CHACE, of Boston, in the county of Suffolk and State of Massachusetts, have invented certain new and useful Improvements in Velocipedes, of which the following is a specification.

My invention relates to velocipedes generally, and particularly to that class commonly known as "tricycles."

It is the object of the invention to economize power and gain speed in the operation of the tricycle.

It is also the object of the invention to provide an improved spring-seat which shall be more comfortable and commodious than those now employed.

My invention comprises a driving-wheel which is adapted to be operated by means of levers through the medium of clutch mechanism, the said driving-wheel engaging a wheel arranged on the main axle and connected with the same by means of a clutch mechanism, so that by the movement of the levers the wheels will be operated to drive the machine ahead, while the manner in which the wheel on the main axle is connected with the latter permits of the ready movement of the machine backward.

My invention also comprises a seat supported upon springs operating at various points near its edge or circumference, so that it may yield from a horizontal position when borne upon at any point touching an imaginary line radiating from its center or yield bodily in a vertical direction.

My invention will first be described in connection with the annexed drawings and letters of reference marked thereon, forming a part of this specification, and then be pointed out in the appended claims.

In the drawings, Figure 1 is a perspective view of a tricycle embodying my improvements. Fig. 2 is a top plan view of the same, the seat being removed. Fig. 3 is a side view of the portion of the clutch mechanism which is attached to the axle to be driven and the clutching-dog and its immediate adjuncts attached to the part of the clutch that is operated by the lever. Fig. 4 is a front view of a clutch mechanism that may be employed in

the invention. Fig. 5 is a detail, partially in section, showing the manner of supporting the seat in my improved tricycle.

In the drawings, *a* designates the main axle provided with the usual wheels *b*. Upon the main axle *a* is arranged a gear *c*, provided upon one, or it may be both, sides with a clutch mechanism *d*, secured to the shaft. This clutch is so devised as that when the gear *c* is driven forward, as indicated by the arrow 1 in Fig. 2, the clutch will be engaged or locked with the said gear and be impelled in the same direction; but when the gear is left free the wheels *b* and axle *a* may be run backward with entire freedom.

e designates an axle journaled in suitable bearings connected with the hounds *f*, and *g* designates a gear-wheel fixed upon axle *e* and constructed and arranged to engage and drive gear-wheel *c*. A clutch mechanism *h*, similar to clutch mechanism *d*, is arranged on each end of axle *e*, the part of each of which clutch mechanism movably arranged on axle *e* being connected with a lever *i*. The construction and arrangement of the clutch mechanism are such that as the levers are moved backward and forward the gear-wheel *g* will be impelled in the direction indicated by the arrow 2.

In Figs. 3 and 4 I have shown a clutch mechanism that is well suited for the purposes hereinbefore mentioned, though any similar contrivance calculated to perform the same function may be employed. In the said figures, *j* designates the part of the clutch which is fixed to the axle *e* and gear *c*, and *k* the part that is attached to axle *a* and levers *i*. The part *j* is recessed in its side, so as to admit of the part *k* partially entering and operating therein, as indicated in dotted lines in Fig. 4. The part *k* is provided on its inner face with a pivoted dog *l*, adapted to rest on a pin *m*, and barely out of contact with the face *n* of rim *o* on part *j* when the part *k* is moved in the direction of the arrow in Fig. 3; but when the said part *k* is moved in a direction opposite to that indicated by the arrow the drag-spring *p*, connected with the dog *l*, will move the latter, so as to bring its free end into engagement with the face *n* of rim *o* and so

lock the two parts together, as will be readily understood. The moment the part *k* is moved in the direction of the arrow in Fig. 3 the free end of the dog *l* will be disengaged from the face *n* of rim *o*, and the spring *p*, dragging on the face of part *j*, will move the dog back upon pin *m*.

q designates the seat, which is provided with three, or it may be more, legs *r*, which 10 rest upon springs *s*, arranged in socketed standards *t*, extending up from a frame *u*, supported upon the hounds *f* and axle *a*. Any suitable means may be provided for preventing the legs *r* from bounding out of the sockets of standards *t*.

v designates the forward guide-wheel suitably arranged in a frame which is pivotally connected by a bolt *w* to the forward end of the hounds *f*, which may be provided with a 20 rack *x*, which engages with a pinion *y* on the rear end of the frame of the guide-wheel, said frame being also provided with a cross bar *z*, upon which the feet of the operator may rest when the machine is being impelled. With 25 this construction great power can be easily exerted by the occupant of the seat *q* to drive the machine ahead, and with his feet resting upon the cross-bar *z* it can be readily guided in any desired course.

30 By varying the respective sizes of the gears *c* and *g* the speed at which the machine may be run with respect to the time in which the levers *i* are operated may be regulated to suit varying purposes.

35 By providing a clutch mechanism to connect gear *c* with axle *a*, I am enabled, when required by necessity, to run the machine backward.

It is obvious that changes may be made in

the form and arrangement of parts comprising my invention without departing from its nature or spirit. For example, the gears *c* and *g* might be constructed as sprocket-wheels and connected by means of a chain arranged on the said wheels.

What I claim is—

1. In a velocipede, the combination of the driving-wheel, its axle, a clutch mechanism to operate the said axle with a lever for operating the clutch mechanism, the main axle, 50 a gear-wheel thereon engaged by the first-mentioned wheel, and a clutch mechanism to connect the gear on the main axle with the latter, as set forth.

2. In a velocipede, the combination, with 55 the driving-wheel and its axle, of the levers *i*, connecting mechanism between the said levers and wheel, whereby the latter may be operated, the main axle and the wheel *c* thereon, and a clutch mechanism for connecting the latter gear with the main axle when the said gear is operated to move the velocipede forward, as set forth.

3. In a velocipede, the combination, with a supporting-frame, of socketed standards connected with said frame, springs in said sockets, a seat, and legs connected with said seat and extended into said sockets and resting upon the said springs, as set forth.

In testimony whereof I have signed my name 70 to this specification, in the presence of two subscribing witnesses, this 14th day of January, A. D. 1890.

ALBERT F. CHACE.

Witnesses:

ARTHUR W. CROSSLEY,
A. D. HARRISON.
